UNITED STATES PATENT OFFICE.

SILAS H. WOODARD, OF SCARSDALE, NEW YORK.

HULL CONSTRUCTION.

1,318,712.

Specification of Letters Patent. Patented Oct. 14, 1919.

Application filed September 26, 1917. Serial No. 193,224.

To all whom it may concern:

Be it known that I, SILAS H. WOODARD, a citizen of the United States, and a resident of Scarsdale, in the county of Westchester 5 and State of New York, have invented certain new and useful Improvements in Hull Construction, of which the following is a specification, reference being made to the accompanying drawings, forming a part 10 thereof.

My invention relates to improvements in the methods of construction and building of ships and floating bodies generally, the objects being, among other things, to form the 15 hull construction of reinforced concrete preferably of cellular formation providing a double bottom, with a wooden outer covering or sheathing, which sheathing shall provide not only a form for the casting of the 20 concrete, but shall also thereafter serve the purpose of water-proofing the concrete hull against seepage, thereby protecting the concrete and the reinforcing iron or steel from deterioration by the action of sea water. 25 The wooden sheathing also serves to protect the concrete hull from chipping and cracks caused by knocks and blows against piers or other objects with which the ship comes in contact.

30 A further aim of my invention is to provide novel means and methods by which the wooden sheathing is secured both to the concrete body and the reinforcing rods embedded in the concrete in such a manner that the 35 various parts comprising my improved hull construction will be so united as to increase very greatly the strength and stability of the hull as a whole.

With these and other objects in view, my 40 invention consists in the novel features of methods of construction and combination of parts hereinafter more fully described and particularly pointed out in the appended claims.

45 Referring to the drawings, Figure 1 is a vertical sectional view of one-half of my improved hull construction, such view being sufficient to show the invention.

Fig. 2 is an enlarged fragmentary sectional view taken on the line 2—2 of Fig. 1; and

Fig. 3 is an enlarged fragmentary sectional view taken on the line 3—3 of Fig. 2.

Similar numerals refer to similar parts 55 throughout the several views.

In the drawings I have shown my im-

proved hull construction as comprising the keel 4 from which are laid outwardly in the usual longitudinal formation the wooden planks 5 which are built and secured together within an outer frame (not shown) by any of the common methods of carpenter construction, such planks 5 forming the wooden covering or sheathing 6 for the inner reinforced concrete which constitutes the 60 body of my improved hull construction. Preferably I form the reinforced concrete body in a cellular form thereby providing a double bottom with water-tight compartments for the ship. After the wooden 70 sheathing 6 has been constructed I erect a series of collapsible forms extending laterally and then upwardly from the keel 4 and bottom to provide the hollow cells 7 between the ribs 8 and space for the formation of the 75 inner and outer bottoms 9 and 10 respectively. These forms may be spaced apart from one another and from the reinforcements shown in Fig. 2 by any of the usual methods, preferably by construction bolts 80 (not shown), which may be left in place when the concrete is poured to form the main inner body of the hull. Since such forms are well-known in this art, they are not shown in the drawings. Between such 85

forms in the spaces to be subsequently filled with concrete for the ribs 8 and the bottoms 9 and 10 I suspend in any suitable manner the reinforcing rods for the concrete construction. Referring to Figs. 2 and 3, the 90 longitudinal rods 11 are for the inner bottom 9 and the longitudinal rods 12 for the outer bottom 10; 13 are the transverse rods for the inner bottom 9 and 14 the transverse rods for the outer bottom 10. 15 indicates 95 the cross rods for the ribs 8. This reinforcing rod structure is preferably held in position by the nails or pins 16 extending inwardly through the planks 5 as shown in Fig. 2; such pins may have their inner ends 100 hook-shaped as at 17 to engage and hold the rods 12, or they may be secured to the rods 14.

I may also provide an inner flooring 18 which shall serve as a false bottom for the 105 ship and support the cargo, though this is not essential for my invention. This flooring 18 is formed of a series of planks 19, suitably jointed together, and may be secured to the reinforcing rods 11 by nails or 110 pins 20 as shown in Fig. 2. 21 designates the deck of my improved hull which deck

may be made of concrete and secured to the side walls of the hull in any suitable manner as shown, and 22 is the keelson preferably integral with the inner bottom 9 and outer bottom 10 as shown in Fig. 1.

When the forms and rods have been placed in position as described, the concrete is then poured within the sheathing 6 and inner flooring 18 to form the inner and outer bottoms 9 and 10 and the ribs 8, the planking of the inner flooring being added as the concrete is poured. When the concrete has set the collapsible forms are removed from the series of the cellular spaces 7 formed through suitably located man-holes (not shown). The body of concrete may be made of any desired thickness according to the strength and weight of hull construction desired, the thickness of the body of concrete forming the self-sustaining construction being preferably greater than the outer sheathing, as shown in Figs. 2 and 3. It will be observed that the concrete body of the hull is fully protected both inside and out against chipping and breakage due to sharp blows, and that the nails or pins 16 and 20 serve not only to hold the wooden sheathing 6 and inner flooring 18 securely in place, and strongly attached to their respective concrete bottoms, but also may act to support and hold the reinforcing rods in position, thereby increasing the unity and solidarity of the combined parts forming the hull construction. By my invention as hereinbefore described a hull construction is provided of practically one piece having an exceptionally strong and rigid structure, while the outer sheathing prevents injurious seepage through the concrete bottom 10, while acting as a buffer against destructive blows.

I claim as my invention:—

1. The method of forming a unitary composite hull construction which consists in first laying an outer protective sheathing, then removably attaching inside said sheathing and in proximity thereto spaced-apart forms, then laying reinforcements in the spaces between the sheathing and forms and securing said reinforcements to the sheathing, and finally molding concrete against the sheathing and around the reinforcements to provide the main strength of the hull.

2. The method of forming a composite hull construction which consists in first laying an outer protective wooden sheathing, then removably attaching in proximity thereto spaced-apart forms inside of said sheathing, then laying transverse reinforcements between the sheathing and also the separated forms and securing said reinforcements to the sheathing, and finally molding concrete against the sheathing and around

the reinforcements and also between and around said separated forms to provide the main strength of the hull.

3. A unitary hull construction comprising an inner integral body of concrete of sufficient thickness to constitute a self-sustaining hull body providing the main strength of the hull, said concrete body consisting of spaced-apart inner and outer bottoms with suitably spaced-apart upright ribs therebetween and reinforcing rods rectangularly disposed and interiorly embedded in said bottoms and ribs, an outer protective wooden sheathing conforming substantially at all points to the desired contour of the outer bottom by having said concrete bottom molded and compacted indivisibly thereto, and interlocking means affixed to and passing through said sheathing and concrete and secured to said embedded reinforcing rods to form a unitary composite hull construction.

4. A composite hull construction comprising an inner integral body of concrete of sufficient thickness to constitute a self-sustaining hull body providing the main strength of the hull, said body consisting of suitably spaced apart inner and outer bottoms with suitably spaced-apart upright ribs therebetween, longitudinal and transverse reinforcing rods interiorly embedded in said bottoms and ribs, an outer protective wooden sheathing of less thickness than said concrete body and conforming substantially at all points to the desired contour of the outer bottom which has been molded and compacted indivisibly against said sheathing, and interlocking means affixed to and passing through said sheathing and concrete and secured to said longitudinal reinforcing rods to form a unitary composite hull construction.

5. A composite hull construction comprising an inner integral body of concrete of sufficient thickness to constitute a self-sustaining hull body providing the main strength of the hull, said body consisting of suitably spaced apart inner and outer bottoms with suitably spaced-apart upright ribs therebetween, longitudinal and transverse reinforcing rods interiorly embedded in said bottoms and ribs, an outer protective wooden sheathing of less thickness than said concrete body and conforming substantially at all points to the desired contour of the outer bottom which has been molded and compacted indivisibly against said sheathing, and pins affixed to and passing through said sheathing and concrete and secured to said longitudinal reinforcing rods to form a unitary composite hull construction.

SILAS H. WOODARD.
